UNITED STATES PATENT OFFICE

EUGENIA M. HOEY, OF SAN FRANCISCO, CALIFORNIA

DESIGN FOR A COMBINATION BED AND DIVAN

Application filed May 24, 1932. Serial No. 43,889. Term of patent 7 years.

To all whom it may concern:

Be it known that I, EUGENIA M. HOEY, a citizen of the United States, residing at the city and county of San Francisco, State of California, have invented a new, original, and ornamental Design for a Combination Bed and Divan, of which the following is a specification, reference being had to the accompanying drawing forming part thereof.

The figure is a perspective view of a combination bed and divan embodying my design.

I claim:

The ornamental design for a combination bed and divan, substantially as shown.

EUGENIA M. HOEY.
